UNITED STATES PATENT OFFICE.

GEORGE S. CLOW, OF COLUMBUS, OHIO.

MACHINE FOR TENONING AND BORING IMPLEMENT-HANDLES.

SPECIFICATION forming part of Letters Patent No. 755,359, dated March 22, 1904.

Application filed October 14, 1903. Serial No. 177,050. (No model.)

To all whom it may concern:

Be it known that I, GEORGE S. CLOW, a citizen of the United States, residing at Columbus, in the county of Franklin and State of Ohio, have invented certain new and useful Improvements in Machines for Tenoning and Boring Implement-Handles; and I do hereby declare the following to be a full, clear, and exact description of the invention, such as will enable others skilled in the art to which it appertains to make and use the same.

The object generally of this invention is to provide an improved machine for simultaneously tenoning and boring an implement-handle, whereby time and labor are saved.

Special objects, among others, are to provide an automatically-operative gage or stop and an automatically-operative chuck or holder for the handle while being tenoned and bored, so that the only manual operations required are the insertion into and removal from the chuck of the sticks constituting the handles, and means whereby the tenoning and boring tool is made self-clearing.

The invention consists in the combinations of parts hereinafter described and claimed.

In the accompanying drawings, illustrating one embodiment of the invention, Figure 1 is an elevation taken at the left-hand side of the machine as faced by the attendant. Fig. 2 is a top plan view. Fig. 3 is a section on the line $x-x$, Fig. 2. Fig. 4 is a front view of the chuck and operating devices with the front covering-plate removed. Fig. 5 is a diametrical section of the chuck. Fig. 6 is a detail of the tenoning device or shaper. Fig. 7 is a section of the same on line $y-y$, Fig. 6. Fig. 8 is a detail of the stop or gage and its operating devices.

1 designates a bed that is supported upon legs 1^a . The bed supports a slide or carriage 2, having separated bearing-containing parts 2^a rising therefrom that in turn support a rotatable mandrel or shaft 3, having a belt-pulley 3^a between the bearing-containing parts 2^a for the application of the necessary power to turn the mandrel. This mandrel 3 has an enlarged forward end 3^b , into which is screwed the threaded shank of the tool-holder 4. The tool-holder 4 contains an appropriate knife or

knives 4^a for tenoning or shaping the outer side or ferrule-receiving portion of the stick and a bit 4^b , located in the axis of the tool-holder. The bit 4^b is preferably removable from the tool-holder and is locked in place after the holder has been screwed up into place by means of a set-screw 3^c , passed through the end 3^b and a hole in the threaded shank of the tool-holder and having its end pinching the bit. The set-screw also prevents the tool-holder from turning in its seat. The rear end of the mandrel turns against a brass bearing 3^m , seated in a box 3^n to take the thrust of the mandrel when working, said brass bearing being supported by one or more adjustable set-screws 3^o to compensate for wear.

Journalized on an appropriate bracket 5^a at the rear end of the bed is a shaft 5, standing at right angles to the mandrel 3. The shaft 5 carries at its left-hand end opposite the rear end of the mandrel 3 a groove-cam 5^b , the groove of which engages a stud 3^d , secured to and projecting from the rear end of the tool-carriage 2. The groove of the cam is of such form, substantially as shown, that it moves the tool-carriage forward and backward twice in one revolution of the cam. The backward movement between the two forward movements is for the purpose of allowing the tool to clear itself of shavings and chips.

Journalized in brackets 6^a at the right-hand side of the bed is a shaft 6, standing parallel to the mandrel 3. This shaft contains a belt-pulley 6^b , and power is transmitted from this shaft to the shaft 5 by means of a miter-gear 6^c on the rear end of the shaft 6, meshing with a similar gear 5^e on the shaft 5.

Secured to the front end of the bed is the chuck for holding the stick constituting the handle when it is tenoned and bored. This chuck comprises a frame-plate 7, several radially-arranged sliding shanks 7^a , having clamping-jaws 7^{aa} and pins 7^b , and a disk 7^c , having eccentric slots 7^d engaging the pins 7^b , so that when the disk 7^c is turned the jaws 7^{aa} are moved inward or outward, according to the direction in which the disk is turned. Attached to the disk 7^c and extending laterally therefrom and above the shaft 6 is a lever-arm 7^e , having a downward projection 7^f , prefer-

ably provided with an antifriction-roller 7^e. The opening between the clamping-jaws 7^{aa} is in the line of the axis of the tool-holder 4. The shaft 6 under the roller 7^e is furnished 5 with a cam 6^d, shaped and secured to the shaft, so as to act on the roller 7^e and lift the roller-arm 7^e and separate the clamping-jaws 7^{aa} to permit a handle that is to be tenoned and bored to be inserted and the removal of the 10 handle after it has been so treated, and the lever-arm 7^e can be weighted or provided with a spring 7^h, attached to a fixed part of the machine to hold the jaws closed on the handle to secure or chuck it tightly while being tenoned 15 and bored.

The gage or stop for determining the distance the handle to be treated shall be inserted into the chuck consists of a lever 8, fulcrumed on small standards 8^b, adjustable and 20 fixable on the bed 1, so that the inner end of the lever can stand across the path of the tool-holder at the desired distance from the chuck. The outer end of the lever 8, which is provided with an antifriction-roller 8^a, extends 25 over the shaft 6, which latter is provided with a cam 6^e, shaped to depress and hold the inner end of the lever out of the way when the tenoning and boring operation takes place and permit that end to rise when it is to serve as 30 a stop or gage, the lever being of sufficient weight at its outer end or weighted or provided with a spring for that purpose.

In operation the power-shaft 6 and mandrel are driven with a constant motion. The workman inserts the end of a stick that is to constitute the handle of the fork, rake, hoe, or other implement into the chuck, when the jaws thereof are separated, the gage limiting the extent to which the stick is insertible. The 35 jaws of the chuck then close tightly on the stick, and the gage automatically moves down out of the way. After this the tenoning and boring tool moves up onto the end of the stick and shapes it externally for the usual ferrule 40 and bores it internally for the shank of the implement; but by reason of the shape of the groove-cam 5^b at the rear of the machine the cutting and boring tool makes two forward and two rearward movements, the first rearward 45 movement being sufficient to permit the tool-holder to clear itself of shavings and chips, and therefore to do clean perfect work. The rapid motion and flaring shape of the opening of the tool-holder effects this automatically through 50 centrifugal force on the shavings and chips. Thus it will be observed that both the tenoning and boring of the handle are effected simultaneously and that all the operations except the mere insertion and removal of the handles 55 from the chuck are performed automatically.

What I claim, and desire to secure by Letters Patent, is—

1. In a machine for tenoning and boring implement-handles, the combination of a tool for 65 simultaneously tenoning and boring the han-

dle-blank, a reciprocating carriage for supporting the tool, means for rotating the tool, and means for automatically gaging and chucking or holding the handle-blank while the tenoning and boring tool is moved onto it. 70

2. In a machine for tenoning and boring implement-handles, the combination of a tool for simultaneously tenoning and boring the handle-blank, a reciprocating carriage for supporting the tool, means for rotating the tool, 75 means for automatically chucking or holding the handle-blank while the tenoning and boring tool is moved onto it, and means for reciprocating the tool-carriage twice during one operation of the chucking device. 80

3. In a machine for tenoning and boring implement-handles, the combination of a tool for simultaneously tenoning and boring the handle-blank, a reciprocating carriage for supporting the tool, means for rotating the tool, 85 means for automatically chucking or holding the handle-blank while the tenoning and boring tool is moved onto it, a stop or gage for limiting the insertion of the handle-blank into the chucking device, and means for automatically moving said stop or gage into operative position when the chuck is inoperative and moving said stop or gage out of operative position when the handle is chucked. 90

4. In a machine for tenoning and boring implement-handles, the combination of a tool for simultaneously tenoning and boring the handle-blank, a carriage for supporting the tool, and means for reciprocating the same, means for rotating the tool, a chucking device and a gage, and a shaft having cams for operating said chucking device and gage. 95

5. In a machine for tenoning and boring implement-handles, the combination of a tool for simultaneously tenoning and boring the handle-blank, a carriage for supporting the tool, and means whereby the carriage may be reciprocated, means for rotating the tool, a chucking device and a gage, and a shaft having cams for operating the chucking device 100 and gage, and means for connecting the said shaft and the means for reciprocating the aforesaid carriage whereby the same may be simultaneously operated. 110

6. In a machine for treating or shaping the tool-holding end of implement-handles, the combination of a tool for cutting said end of the handle-blank, a reciprocable carriage for supporting the tool, means for automatically reciprocating the carriage, means for rotating the tool, means for automatically chucking or holding the handle-blank while the cutting-tool and handle-blank are brought together to do the cutting. 115

7. In a machine for treating implement-handles, the combination of a tool for cutting the implement-holding end of the blank thereof, a support for the tool, means for rotating the tool, means for automatically gaging and chucking or holding the handle-blank, and 120

means for automatically bringing the tool and the handle-blank together to effect the cutting operation.

8. In a machine for treating implement-handles, the combination of a tool for cutting the implement-holding end of a handle-blank, a reciprocable carriage for supporting the tool, a cam for reciprocating said carriage, and means for rotating the tool, a power-shaft 6, 10 a gage, and a chucking device, cams on the shaft 6 for operating the chuck and gage, and gearing for operating the tool-carriage-reciprocating cam from the shaft 6.

9. In a machine for treating implement-handles, the combination of a tool for cutting the implement-holding end of the handle-blank, a 15

reciprocable carriage for supporting the tool, means for rotating the tool, a cam for reciprocating said carriage, a power-shaft 6, a chucking device, an adjustable gage 8 for limiting the insertion of the handle into the chuck, cams on the shaft 6 for operating the chuck and gage, substantially as described, and gearing for operating the tool-carriage-reciprocating cam from the shaft 6. 20 25

In testimony whereof I affix my signature in presence of two witnesses.
